The present invention relates to mass spectrometers for determining the ratio of the concentrations of two constituents of a gas mixture.

As is well known, a mass spectrometer generally contains an ionization chamber in which the molecules of a gas to be examined are subjected to bombardment by an electron stream so that the gas molecules are ionized. Under the action of an electric field set up by the accelerating electrode or electrodes, the electrons produced are conveyed at a certain velocity to a space in which they are subjected to the action of a magnetic field, an electric field, or both a magnetic and an electric field. Consequently, the ions travelling through this space are deflected from their initially rectilinear path, the degree of deflection depending upon the mass-charge ratio of each ion. In the field, the paths of the ions become substantially circular and separate ion beams are formed each consisting of ions of the same constituent of the initial gas mixture. By varying the voltage at the accelerating electrodes or the deflecting field, each beam can be focussed onto the collector electrode. The strength of the current to the collector is a measure of the concentration of the constituent of the mixture from which the ions concerned originate. Generally, the collector current is very weak and must be amplified before it can be measured.

In a known mass spectrometer, an image of the current to the collector is produced on the screen of a cathode-ray oscillosograph as a function of the accelerating voltage. The curve produced exhibits a number of maximum values corresponding to the components of the gas mixture, so called mass peaks, the heights of which are a measure of the concentrations of these components. A comparison between the heights of two mass peaks indicates the ratio of the concentrations of the corresponding two constituents of the mixture.

A device is known in which the aforementioned ratio is determined by imparting to the voltage at the accelerating system in cyclic sequence the values at which the ions of each constituent of the mixture to be examined are focussed onto the collector electrode. This is effected by means of a rotating step switch which successively actuates a number of relays through which the accelerating voltages (which are taken from potentiometers) are supplied to the accelerating electrodes of the mass spectrometer. The output circuit of the amplifier for the collector currents is connected to a number of adjustable attenuators, for example potentiometers. The output voltages of attenuators are successively supplied, through further relay contacts, in synchronism with the variation of the accelerating voltages, to a comparison device. The attenuators are adjusted so that in the comparison device the voltage peaks corresponding to the various masses are equal to one another. Thus, the adjustment of the attenuators determines the concentrations of the constituents of the mixture. This device has the advantage that the measurements are only slightly affected by acci-

dental variations of the sensitivities of the mass spectrometer and the amplifier.

The present invention relates to a mass spectrometer of this kind for determining the ratio of the concentrations of two constituents of a gas mixture to be analyzed. It is an object of the invention to provide a comparatively simple device by which this ratio can be determined rapidly and accurately.

In accordance with the present invention, shortly before each periodic change of the accelerating voltage or, in general, of the quantities which determine the movement of the various ions, the ion flow is interrupted. After a certain period of time the ion flow is restored again, so that an interrupted sequence of square waves is produced in synchronism with the periodic changes of the accelerating voltage. Two capacitors are charged to the mean voltages of the alternating voltage waves which correspond to the constituents of the mixture.

The peak detection of the arrangement of the invention results in independence of the switching times of the switches. The switches may consequently be simple bipolar relays fed from the alternating current supply. The periodic interruption of the ion stream ensures that no mass peaks can occur which correspond to constituents of the mixture whose mass peaks lie between those of the constituents whose concentration ratio is to be ascertained.

A switch, which is in synchronism with the interruption of the ionization, for part of the duration of the voltage wave corresponding to one of the constituents of the gas mixture, completes the output circuit and supplies the voltage waves which are passed to a double-pole switch which operates at half the frequency of the first-mentioned switch and through which two capacitors are alternately connected to the output circuit and charged.

The differences of the voltages across the capacitors can be measured by means of a direct-current instrument. The attenuator producing the output voltage which corresponds to the gas having the highest mass peak is adjusted so that the measuring instrument indicates zero. In this arrangement, only a single attenuator is required; the other voltage can be passed on unattenuated. The measuring instrument preferably has its zero indication at the center of its scale.

When using the alternating current supply as the voltage supply source of the relays, 25 measurements per second are performed for each of the constituents of the mixture, so that the influence of accidental variations of the ion source and the amplifier used are eliminated.

The attenuator can be adjusted automatically by means of a servomechanism. In this event, the voltage difference if required after amplification, acts upon a motor driving the operating mechanism of the attenuator.

The voltage difference can be used for an automatic control of a composition of the gas mixture, in which event the voltage difference is used as the control voltage of the controller.

The ratio of the concentrations of the two constituents is determined by the adjustment of the attenuator.

In order that the invention may readily be carried into effect, it will now be described, by way of example, with reference to the accompanying drawing, in which:

Fig. 1 is a schematic diagram of an embodiment of the circuit arrangement of the present invention;

Fig. 2 is a graphical presentation of various voltages produced at various points of the embodiment of Fig. 1 as functions of the time, indicating the switching instants of various relays of the embodiment of Fig. 1; and

Fig. 3 is a schematic diagram of an embodiment of a circuit arrangement which may be utilized in the embodiment of Fig. 1.

In Fig. 1, a spectrometer tube 1 of a type known in

the art, whose design and operating characteristics are assumed to be known, comprises a grid 12 by means of which the electron current ionizing the gas mixture can be controlled, an electrode 13 by means of which the ions can be accelerated to a greater or lesser extent and a collector electrode 14. It is assumed that the ions are acted upon by a magnetic field in a manner whereby they describe substantially circular paths in the field.

The collector currents flow through a high resistance 5 and the voltages produced across said resistor are amplified in an amplifier 2. The amplifier 2 ensures that despite the high input resistance and input capacitance, a satisfactory frequency characteristic is obtained so that the square-wave input voltages are transmitted as square-wave output voltages.

By means of a switch *a*, a voltage of the form shown in Fig. 2a is applied to the ionization electrode 12.

The switch *a* can be designed as a bipolar relay which is fed from the source of power supply. Thus, the ion source is alternately interrupted and restored at a frequency of 50 cycles per second so that each time during 0.01 second ions are produced and during the next 0.01 second there is no ionization. Obviously, other means may be used to suppress the ion beam, such as for example, a highly deflecting auxiliary field set up in, or in the vicinity of, the ion source.

An accelerating voltage, which is a square wave voltage having a frequency of 25 cycles per second, is applied to the accelerating electrode 13. The variation of the voltage applied to the electrode 13 is shown in Fig. 2b. The value of the accelerating voltage is raised from V to $V + \Delta V$ at the middle of the interval that no ions are produced at an interval of 0.02 second later, that is, at an instant that no ions are produced, the voltage is again given the value V . The value V corresponds to the mass peak of one constituent and the value $V + \Delta V$ corresponds to the mass peak of the second constituent of the mixture.

At the collector, a current appears of the form shown in Fig. 2c. The voltage at the point A in the output circuit of the amplifier 2 varies in the same manner. High and low voltage waves, which correspond to the various concentrations in the gas mixture, succeed one another.

The amplified voltage is set up across a potentiometer 6. By means of a switch *d* either the point A or the sliding contact of the potentiometer 6 is periodically connected to the point B. Consequently, the highest square wave is attenuated and the voltage at point B has the form shown in Fig. 2e. The manner in which the switch *d* operates is shown in Fig. 2d. The movable arm of the switch alternately engages the point A fixed contact and the potentiometer 6 sliding contact for 0.02 second. Thus the switch *d* operates at a frequency of 25 cycles per second. Fig. 2e shows the condition in which equality of the pulses has not yet been achieved. As will be shown hereinafter, the sliding contact of the potentiometer 6 is invariably arranged so as to achieve equality.

The voltage of the form shown in Fig. 2e is transmitted by an amplifier 3, which generally comprises only a single cathode follower, to a device for comparing the two voltages. The comparison device comprises a switch *e*, a switch *f* and two capacitors 7 and 8. The switch *e* operates in the manner shown in Fig. 2f and periodically establishes a direct connection to the movable contact of the switch *f* for a certain period of time. The contact *e* is closed shortly after each appearance of a voltage and is opened shortly before it disappears. This may be effected by a simple relay with delayed operation.

Through the switch *f*, the capacitors 7 and 8 are alternately connected to one of the contacts of *e*. This is effected in the manner shown in Fig. 2g at a frequency

of 25 cycles per second and in synchronism with the variation of the accelerating voltage.

The capacitors 7 and 8 are charged by the voltages corresponding with the square-wave voltages shown in Fig. 2e. These voltages are shown in Fig. 2h. Charging may be performed through a resistor *R* in the output circuit of the amplifier 3 and this ensures that the capacitors 7 and 8 are charged to voltages which have substantially the mean value of the voltage of each pulse.

10 The resistor *R* may be of the order of 10,000 ohms and the capacitance values of the capacitors 7 and 8 may be of the order of 1 microfarad.

During the periods in which no voltages are set up at the point A due to ions, the mean potential of said point should be zero. This may be achieved by means of a switch *c* which is shown in Fig. 1 and is closed in the intervals in which there is no voltage. In this event, the amplifier 2 must be coupled to the potentiometer 6 through the capacitor 30. However, this involves an increase of the noise. Noise of frequencies of $25n$ cycles per second (where n is an integer) provides a considerable additional contribution to noise of 25 cycles per second, the frequency band in which measurements are actually carried out. The influence of noise voltages can be eliminated in the manner shown in Fig. 3. The circuit arrangement shown in Fig. 3 also acts as an automatic correction circuit for the zero level. No coupling capacitor is required.

15 In the circuit arrangement of Fig. 3, provision is made of a tube 15 which is connected as a cathode follower. The control grid of the tube 15 is connected to the output of the amplifier 2 and the cathode of said tube, which is connected to a point at negative potential through a high resistance, is also connected to the point A. The junction of two resistors 17 and 17' is connected to an amplifier 18 which is provided with a filter tuned to 50 cycles per second. The filter ensures that the amplifier 18 is not overdriven by its own noise. The output of the filter is connected, through a switch *k* to an RC circuit 21, 22. By means of a tube 23, the output voltages of the RC circuit 21, 22 are amplified and supplied to the grid of the tube 15. The switch *h*, which bridges the resistor 17', and the switch *k* operate in the manner indicated in Fig. 2k; the switch *h* is closed during a pulse and is open for the larger part of the intervals, as is indicated by cross-hatching in Fig. 2k.

20 When the circuit arrangement shown in Fig. 3 is used, there is no increase in the noise, for care is taken that the amplification by the amplifier 2 multiplied by the attenuation in the RC-filter is less than 1.

25 Fig. 1 shows another amplifier 4, to the output of which is connected a switch *g* by means of which the amplified voltage pulses are alternately supplied to capacitor 9 or capacitor 10. A direct current instrument 11, for example a tube voltage measuring circuit, indicates the potential difference between the capacitors. In measuring, the sliding contact of the potentiometer 6 is moved until the instrument 11 indicates zero. The movement of the potentiometer contact may be effected by means of a servomechanism. This arrangement together with the switches *f* and *g* measures the voltage between the capacitors 7 and 8 through a frequency- and phase-selective amplifier with a low noise level. The amplifier 4 is a conventional alternating voltage amplifier.

30 The relays operating at 50 cycles per second may be designed as polarized relays and may be directly connected to the source of power supply. The relays operating at 25 cycles per second may also be controlled from the alternating current supply. The 25 cycle per second relays are preferably designed as electronic frequency dividers, for example flip-flop circuits combined with phase shifters by means of which square-wave voltages having a recurrence frequency of 25 cycles per second are produced, the phases of which can be adjusted at will.

The circuit arrangement of the present invention permits the direct measurement of isotope ratios, even if the masses differ from one another by more than a mass unit.

While the invention has been described by means of a specific example and in specific embodiments, we do not wish to be limited thereto, for obvious modifications will occur to those skilled in the art without departing from the spirit and scope of the invention.

What is claimed is:

1. A mass spectrometer circuit arrangement comprising a spectrometer tube having means for controlling the ionization of a gas mixture in said tube, means for controlling the acceleration of the ions of said gas mixture and means for collecting said ions, switching means for cyclically permitting the ionization of said gas mixture, means for cyclically applying acceleration voltages having different levels of magnitude during consecutive periods to said acceleration controlling means thereby producing an output voltage at said collecting means comprising a series of pulses having consecutive levels of magnitude corresponding to the ions produced by the components of said gas mixture, said switching means and said means for cyclically applying acceleration voltages having a predetermined frequency and phase relationship to each other, means for detecting said output voltage in synchronism with the operation of said switching means to produce at least two voltages having magnitude levels determined by the ions produced by the components of said gas mixture, and means for determining the difference between said two voltages thereby establishing the ratio of the concentrations of ions of the components of said gas mixture.

2. A mass spectrometer circuit arrangement comprising a spectrometer tube having means for controlling the ionization of a gas mixture in said tube, means for controlling the acceleration of the ions of said gas mixture and means for collecting said ions, switching means for cyclically permitting the ionization of said gas mixture, means for cyclically applying acceleration voltages having different levels of magnitude during consecutive periods to said acceleration controlling means thereby producing an output voltage at said collecting means comprising a series of pulses having consecutive levels of magnitude corresponding to the ions produced by the components of said gas mixture, said switching means and said means for cyclically applying acceleration voltages having a predetermined frequency and phase relationship to each other, means for detecting said output voltage in synchronism with the operation of said switching means to produce at least two voltages having magnitude levels determined by the ions produced by the components of said gas mixture, said detecting means comprising at least a pair of capacitors and means for applying said output voltage to said capacitors in synchronism with the operation of said switching means, and means for determining the difference between said two voltages thereby establishing the ratio of the concentrations of ions of the components of said gas mixture.

3. A mass spectrometer circuit arrangement comprising a spectrometer tube having means for controlling the ionization of a gas mixture in said tube, means for controlling the acceleration of the ions of said gas mixture and means for collecting said ions, switching means for cyclically permitting the ionization of said gas mixture, means for cyclically applying acceleration voltages having different levels of magnitude during consecutive periods to said acceleration controlling means thereby producing an output voltage at said collecting means comprising a series of pulses having consecutive levels of magnitude corresponding to the ions produced by the components of said gas mixture, said switching means and said means for cyclically applying acceleration volt-

ages having a predetermined frequency and phase relationship to each other, means for detecting said output voltage in synchronism with the operation of said switching means to produce at least two voltages having magnitude levels determined by the ions produced by the components of said gas mixture, said detecting means comprising at least a pair of capacitors, means for applying said output voltage to said capacitors in synchronism with the operation of said switching means and means for alternately charging said capacitors proportionally to the levels of magnitude of said output voltage in synchronism with the operation of said switching means, and means for determining the difference between said two voltages thereby establishing the ratio of the concentrations of ions of the components of said gas mixture.

4. A mass spectrometer circuit arrangement comprising a spectrometer tube having means for controlling the ionization of a gas mixture in said tube, means for controlling the acceleration of the ions of said gas mixture and means for collecting said ions, switching means for cyclically permitting the ionization of said gas mixture, means for cyclically applying acceleration voltages having different levels of magnitude during consecutive periods to said acceleration controlling means thereby producing an output voltage at said collecting means comprising a series of pulses having consecutive levels of magnitude corresponding to the ions produced by the components of said gas mixture, said switching means and said means for cyclically applying acceleration voltages having a predetermined frequency and phase relationship to each other, means for detecting said output voltage comprising a pair of capacitors and means for applying said output voltage to said capacitors in synchronism with the operation of said switching means whereby each of said capacitors is alternately charged to produce a voltage having a magnitude level determined by the ions produced by a component of said gas mixture, and means for determining the difference between the voltages across said capacitors thereby establishing the ratio of the concentrations of ions of the components of said gas mixture.

5. A mass spectrometer circuit arrangement comprising a spectrometer tube having means for controlling the ionization of a gas mixture in said tube, means for controlling the acceleration of the ions of said gas mixture and means for collecting said ions, switching means for cyclically permitting the ionization of said gas mixture, means for cyclically applying acceleration voltages having different levels of magnitude during consecutive periods to said acceleration controlling means thereby producing an output voltage at said collecting means comprising a series of pulses having consecutive levels of magnitude corresponding to the ions produced by the components of said gas mixture, said switching means and said means for cyclically applying acceleration voltages having a predetermined frequency and phase relationship to each other, means for detecting said output voltage comprising a pair of capacitors, a resistor and means for applying said output voltage to said capacitors through said resistor in synchronism with the operation of said switching means whereby each of said capacitors is alternately charged proportionally to the mean value of a magnitude level of said output voltage to produce a voltage having a magnitude level corresponding to the concentration of ions produced by a component of said gas mixture, and means for determining the difference between the voltages across said capacitors thereby establishing the ratio of the concentrations of ions of the components of said gas mixture.

6. A mass spectrometer circuit arrangement comprising a spectrometer tube having means for controlling the ionization of a gas mixture in said tube, means for controlling the acceleration of the ions of said gas mixture and means for collecting said ions, switch means for cyclically permitting the ionization of said gas mix-

ture, means for cyclically applying acceleration voltages having different levels of magnitude during consecutive periods to said acceleration controlling means thereby producing an output voltage at said collecting means comprising a series of pulses having consecutive levels of magnitude corresponding to the ions produced by the components of said gas mixture, said switching means and said means for cyclically applying acceleration voltages having a predetermined frequency and phase relationship to each other, means for detecting said output voltage comprising a pair of capacitors, second switching means interposed between said collecting means and said capacitors for applying said output voltage to said capacitors in synchronism with the operation of said first-mentioned switching means and third switching means interposed between said second switching means and said capacitors for alternately applying the voltage passed by said second switching means to each of said capacitors whereby each of said capacitors is alternately charged to produce a voltage having a magnitude level determined by the ions produced by a component of said gas mixture, and means for determining the difference between the voltages across said capacitors thereby establishing the ratio of the concentrations of ions of the components of said gas mixture.

7. A mass spectrometer circuit arrangement comprising a spectrometer tube having means for controlling the ionization of a gas mixture in said tube, means for controlling the acceleration of the ions of said gas mixture and means for collecting said ions, switching means for cyclically permitting the ionization of said gas mixture, means for cyclically applying acceleration voltages having different levels of magnitude during consecutive periods to said acceleration controlling means thereby producing an output voltage at said collecting means comprising a series of pulses having consecutive levels of magnitude corresponding to the ions produced by the components of said gas mixture, said switching means and said means for cyclically applying acceleration voltages having a predetermined frequency and phase relationship to each other, means for detecting said output voltage comprising a pair of capacitors, second switching means interposed between said collecting means and said capacitors for applying said output voltage to said capacitors in synchronism with the operation of said first-mentioned switching means and third switching means interposed between said second switching means and said capacitors for alternately applying the voltage passed by said second switching means to each of said capacitors at half the frequency of operation of said second switching means whereby each of said capacitors is alternately charged to produce a voltage having a magnitude level determined by the ions produced by a component of said gas mixture, and means for determining the difference between the voltages across said capacitors thereby establishing the ratio of the concentrations of ions of the components of said gas mixture.

8. A mass spectrometer circuit arrangement comprising a spectrometer tube having means for controlling the ionization of a gas mixture in said tube, means for controlling the acceleration of the ions of said gas mixture and means for collecting said ions, switching means for cyclically permitting the ionization of said gas mixture, means for cyclically applying acceleration voltages having different levels of magnitude during consecutive periods to said acceleration controlling means thereby producing an output voltage at said collecting means comprising a series of pulses having consecutive levels of magnitude corresponding to the ions produced by the components of said gas mixture, said switching means and said means for cyclically applying acceleration voltages having a predetermined frequency and phase relationship to each other, means for detecting said output voltage comprising a pair of capacitors, second switch-

ing means interposed between said collecting means and said capacitors for applying said output voltage to said capacitors in synchronism with the operation of said first-mentioned switching means, said second switching means applying said output voltage to said capacitors for a period of time beginning relatively soon after the initiation of operation of said first-mentioned switching means and ending relatively shortly before the cessation of operation of the said first-mentioned switching means, and third switching means interposed between said second switching means and said capacitors for alternately applying the voltage passed by said second switching means to each of said capacitors at half the frequency of operation of said second switching means whereby each of said capacitors is alternately charged to produce a voltage having a magnitude level determined by the ions produced by a component of said gas mixture, and means for determining the difference between the voltages across said capacitors thereby establishing the ratio of the concentrations of ions of the components of said gas mixture.

9. A mass spectrometer circuit arrangement comprising a spectrometer tube having means for controlling the ionization of a gas mixture in said tube, means for controlling the acceleration of the ions of said gas mixture and means for collecting said ions, switching means for cyclically permitting the ionization of said gas mixture, means for cyclically applying acceleration voltages having different levels of magnitude during consecutive periods to said acceleration controlling means thereby producing an output voltage at said collecting means comprising a series of pulses having consecutive levels of magnitude corresponding to the ions produced by the components of said gas mixture, said switching means and said means for cyclically applying acceleration voltages having a predetermined frequency and phase relationship to each other, means for detecting said output voltage comprising a pair of capacitors, second switching means interposed between said collecting means and said capacitors for applying said output voltage to said capacitors in synchronism with the operation of said first-mentioned switching means, said second switching means applying said output voltage to said capacitors for a period of time beginning relatively soon after the initiation of operation of said first-mentioned switching means and ending relatively shortly before the cessation of operation of the said first-mentioned switching means, and third switching means interposed between said second switching means and said capacitors for alternately applying the voltage passed by said second switching means to each of said capacitors at half the frequency of operation of said second switching means whereby each of said capacitors is alternately charged to produce a voltage having a magnitude level determined by the ions produced by a component of said gas mixture, said third switching means comprising a two-position switch, and means for determining the difference between the voltages across said capacitors thereby establishing the ratio of the concentrations of ions of the components of said gas mixture.

10. A mass spectrometer circuit arrangement comprising a spectrometer tube having means for controlling the ionization of a gas mixture in said tube, means for controlling the acceleration of the ions of said gas mixture and means for collecting said ions, switching means for cyclically permitting the ionization of said gas mixture, means for cyclically applying acceleration voltages having different levels of magnitude during consecutive periods to said acceleration controlling means thereby producing an output voltage at said collecting means comprising a series of pulses having consecutive levels of magnitude corresponding to the ions produced by the components of said gas mixture, said switching means and said means for cyclically applying acceleration voltages having a predetermined frequency and phase relation-

ship to each other, means for detecting said output voltage comprising a pair of capacitors, second switching means interposed between said collecting means and said capacitors for applying said output voltage to said capacitors in synchronism with the operation of said first-mentioned switching means, said second switching means applying said output voltage to said capacitors for a period of time beginning relatively soon after the initiation of operation of said first-mentioned switching means and ending relatively shortly before the cessation of operation of the said first-mentioned switching means, and third switching means interposed between said second switching means and said capacitors for alternately applying

the voltage passed by said second switching means to each of said capacitors at half the frequency of operation of said second switching means whereby each of said capacitors is alternately charged to produce a voltage having a magnitude level determined by the ions produced by a component of said gas mixture, each of said second and third switching means comprising a bipolar relay, and means for determining the difference between the voltages across said capacitors thereby establishing 10 the ratio of the concentrations of ions of the components of said gas mixture.
